United States Patent Office

Des. 197,861
Patented Mar. 31, 1964

197,861

COMBINED VEGETABLE SHREDDER AND JUICE EXTRACTOR

Nicholas H. Knuth, 1720 N. California Ave., Chicago, Ill.

Filed Sept. 7, 1961, Ser. No. 66,630

Term of patent 14 years

(Cl. D55—1)

FIG. 1

FIG. 2

FIG. 3

FIGURE 1 is a perspective view of a combined vegetable shredder and juice extractor showing my new design.

FIGURE 2 is a top view of FIGURE 1, and

FIGURE 3 is a side elevational view of FIGURE 1.

I claim:

The ornamental design for a combined vegetable shredder and juice extractor, as shown.

References Cited in the file of this patent

UNITED STATES PATENTS

2,864,419 WOOCK Dec. 16, 1958